CLAIM

The ornamental design for a defense spray holder as shown and described.

DESCRIPTION

FIG. 1 illustrates a perspective view of a defense spray holder, showing our new design;

FIG. 2 illustrates a front view thereof;

FIG. 3 illustrates a rear view thereof;

FIG. 4 illustrates a top view thereof;

FIG. 5 illustrates a bottom view thereof;

FIG. 6 illustrates a left view thereof; and,

FIG. 7 illustrates a right view thereof.

The broken lines in the figures illustrate the portions of the defense spray holder and form no part of the claimed design.

1 Claim, 7 Drawing Sheets
